5, 1939, Serial No. 288,524. In Great Britain
February 12, 1936

4 Claims. (Cl. 19—1)

This invention relates to the manufacture of
yarns containing staple fibers from yarns com-
posed of continuous filaments, and is divided from
application No. 124,048 for "improvements in the
5 Manufacture of yarns containing staple fibers
from yarns composed of continuous filaments,"
filed February 4, 1937.

According to the present invention yarns con-
taining staple fibers are produced by continu-
10 ously drawing yarns composed of continuous fil-
aments, for example yarns of cellulose acetate
artificial silk or the like, over a razor edge in
such a way that at intervals along the yarn, some
but not all of the filaments are severed.
15 Besides the yarns composed of continuous fil-
aments of cellulose acetate referred to above, yarns
containing continuous filaments of other mate-
rials may also be used for the purpose of the
invention, for example materials having a basis
20 of other organic derivatives of cellulose, regen-
erated cellulosic materials, for example cupram-
monium artificial silk and viscose artificial silk,
and natural silk.

The yarns treated should preferably be lightly
25 twisted but even untwisted yarns may be used
provided that suitable means are adopted to
maintain the necessary coherence between the
severed and the unsevered filaments, for exam-
ple by sizing or by the insertion during winding
30 of twist which runs back from the collecting de-
vice as far, or nearly as far, as the razor edge.
On the other hand it is of advantages that the
filaments in the yarn should not be so closely
packed as to prevent them from spreading some-
35 what during the severing.

The invention is particularly advantageous
when applied to continuous filament yarns whose
volume or bulk has been increased, e. g., by sub-
jecting the yarn, either on its way to the razor
40 edge or in a previous stage, to a false twisting
operation in the course of which the twist in-
serted in the yarn is set, e. g., by the application
of wet steam or other setting agent. In the case
45 of a false twisting operation of this kind the twist
so set in the yarn automatically runs out owing
to the nature of the false twisting operation.
Alternatively the yarn may, in a previous stage,
have been actually twisted prior to or during
50 setting of the twist, in which case the twist
should preferably be removed. Indeed, in the
case either of a twisting or of a false twisting
operation carried out in a previous stage a small
quantity of twist in the reverse direction to that
55 set in the yarn may conveniently be imparted to
the yarn after the setting and removal of twist.

In the case either of a twisting or of a false twist
operation, the setting and removal of twist leaves
the yarn with a greater bulk than it previously
possessed on account of the distortion of the in-
dividual filaments, imposed while the yarn was
temporarily twisted and retained after untwisting.
A yarn whose bulk has been increased in
this manner, and which has been given a small
degree of reverse twist, is particularly conven-
ient for the purposes of the present invention. 5

One form of apparatus according to the pres-
ent invention will now be described in greater
detail with reference to the accompanying draw-
ing, in which:

Fig. 1 is a diagrammatic side elevation of an 15
apparatus according to the invention;

Fig. 2 is a front elevation of a part of Fig. 1;
and

Fig. 3 shows a detail of the apparatus shown 20
in Figs. 1 and 2.

Referring to Figs. 1 and 2, the yarn 1 is drawn
from a stationary package 2 through a balloon
guide 3 and then proceeds directly over an ex-
posed part of the edge of a blade 4 which is of
the wafer type commonly employed in safety 25
razors. The blade 4 is provided with a guard
5 having a gap at 6 in one of its edges through
which gap the yarn is caused to pass. The blade
4 and the guard 5 are secured to a holding plate
7 by means of a nut and bolt 8. The holding 30
plate 7 is carried on a bar 9 and is set at an
acute angle of, e. g., 45°, to the yarn coming to
it so that the yarn is drawn past the edge, and
the filaments are not instantly and simultane-
ously severed. 35

From the edge of the blade at the gap 6 the
yarn passes through a pig-tail guide 10 and
thence round three rollers 11, 12, 13. The roller
11 is a driven roller and drives the rollers 12 and
13 by friction. The rollers 12 and 13 drop into 40
slots 14 and 15 in a bracket 16, the slot 14 open-
ing in front of the bracket so that the roller 12
may be dropped in in such a way that the yarn
is caused to pass over the roller 11, behind the
roller 12 and in front of the roller 13. From the 45
roller 13 the yarn proceeds to the guides 17, 18
of a take-up device by means of which they are
wound on a package 19.

The guide 10 is carried on a long wire 20 which
is pivotally mounted at 21 on the bracket 16. A 50
U-shaped piece of wire 22 is secured to the wire
20 and engages with a disc 23 obliquely secured
to the spindle 24 of the roller 12, as is shown in
Fig. 3. The obliquity of the disc 23 causes the
wire 20 which is connected to the disc 23 by the 55

U-shaped wire 22 to oscillate about the pivot point 21 so that the pig-tail guide 10 oscillates to and fro lengthwise of the exposed edge of the blade 4. In this way the yarn is caused to traverse to and fro along the exposed part of the blade. In order to prevent the accumulation of loose severed filaments beneath the blade 4, a nozzle 34 is provided in order to direct a jet of air against the edge of the blade, and blow any loose filaments away. In place of the nozzle 34 there may be employed a rotating brush or a wiper which may be synchronized with the reciprocation of the thread.

When yarn having a crinkle produced by twisting the yarn, setting the twist therein and removing the twist is employed, it is preferable that the take-up package 19 should be rotated at a speed slightly lower than the peripheral speed of the rollers 11, 12 and 13 so that the crinkle is not pulled out by the tension between the take-up package 19 and the roller 13.

Having described our invention, what we desire to secure by Letters Patent is:

1. Apparatus for the production of yarn containing staple fibers from yarns composed of continuous filaments, said apparatus comprising a blade having a razor-like cutting edge, means for continuously drawing yarns composed of continuous filaments over said edge and means for traversing the yarn along said edge so that at intervals along the yarn some, but not all, of the filaments are severed.

2. Apparatus for the production of yarn con-

taining staple fibers from yarns composed of continuous filaments, said apparatus comprising a blade having a razor-like cutting edge, means for continuously drawing yarns composed of continuous filaments over said edge, a guide for leading the filaments in contact with said edge, and means for reciprocating said guide to and fro parallel to said edge so as to traverse the yarn along said edge whereby at intervals along the yarn some, but not all, of the filaments are severed.

3. Apparatus for the production of yarn containing staple fibers from yarns composed of continuous filaments, said apparatus comprising a blade having a razor-like cutting edge, means for continuously drawing yarns composed of continuous filaments over said edge, said blade being set so as to form an acute angle with the yarn about to cross the edge of said blade, and means for traversing the yarn along said edge so that at intervals along the yarn some, but not all, of the filaments are severed.

4. Apparatus for the production of yarn containing staple fibers from yarns composed of continuous filaments, said apparatus comprising a blade having a razor-like cutting edge, a guard adapted to cover a part of said edge and means for continuously drawing yarns composed of continuous filaments over said edge so that at intervals along the yarn some, but not all, of the filaments are severed.
